United States Patent Office

Des. 217,888
Patented June 23, 1970

217,888

AMPHIBIOUS AIRCRAFT

Cornelius Biemond, 2308 Richards Drive,
Carson City, Nev. 89701

Filed Aug. 19, 1968, Ser. No. 13,182

Term of patent 14 years

Int. Cl. D12—07

U.S. Cl. D71—1

FIG. 2.

FIG. 3.

FIG. 4.

FIG. 5.

FIG. 6.

FIG. 7.

FIG. 1 is a perspective view showing the design of the amphibious aircraft in an attitude of flight;

FIG. 2 is a plan view thereof with the propellers in another position for clarity of illustration;

FIG. 3 is a bottom view thereof with the propellers in another position for clarity of illustration;

FIG. 4 is a left elevational view thereof with the forward landing gear shown in an alternate position;

FIG. 5 is a right elevational view thereof with the forward landing gear shown in an alternate position;

FIG. 6 is a front elevational view thereof with the forward landing gear shown in an alternate position; and

FIG. 7 is a rear elevational view thereof with the forward landing gear shown in an alternate position.

I claim:

The ornamental design for an amphibious aircraft, as shown and described.
